US0D1100726S

(12) **United States Design Patent** (10) **Patent No.:** **US D1,100,726 S**
(45) **Date of Patent:** **** Nov. 4, 2025**

(54) **PLANT GROWTH APPARATUS**

(71) Applicant: **Qiuyang Zhu**, Changde (CN)

(72) Inventor: **Qiuyang Zhu**, Changde (CN)

(**) Term: **15 Years**

(21) Appl. No.: **29/831,921**

(22) Filed: **Mar. 23, 2022**

(51) LOC (15) Cl. **11-02**

(52) U.S. Cl.

USPC **D11/155**; D11/144; D11/145

(58) **Field of Classification Search**

(57) **CLAIM**

The ornamental design for a plant growth apparatus, as shown and described.

DESCRIPTION

FIG. 1 is a perspective view of a plant growth apparatus, showing my new design;

FIG. 2 is a perspective view with the outer door open thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

1 Claim, 8 Drawing Sheets
